UNITED STATES PATENT OFFICE.

SAM. GUST. BERNSTEIN AND MICHAEL SIMONSON, OF NEW YORK, N. Y.

SHOW-BOX FOR TRIMMINGS.

SPECIFICATION forming part of Letters Patent No. 293,844, dated February 19, 1884.

Application filed September 18, 1883. (No model.)

To all whom it may concern:

Be it known that we, SAMUEL G. BERNSTEIN and MICHAEL SIMONSON, of the city, county, and State of New York, have invented 5 a new and Improved Show-Box for Trimmings, of which the following is a full, clear, and exact description.

By the common method of packing and keeping in store trimmings—viz., by reeling them 10 on a board or card and placing the card in a box—they are liable to become rapidly shop-worn. Especially is this true of heavy fringes and marabous.

Our invention seeks to overcome this difficulty; and to this end our invention consists 15 of the several combinations of parts, substantially as hereinafter fully set forth, and pointed out in the claims.

Reference is to be had to the accompanying 20 drawing, forming part of this specification, in which the figure is a perspective view of our new and improved trimming frame and box, the back covering of the frame being raised and one corner broken away to show the construction of the frame, and with the box partly broken away to show the supports for the frame.

A represents the frame, and B represents the box, which latter is provided at its corners with 30 the supporting-posts b b, for supporting the frame A up from the bottom of the box, so that the fringe C, held in the frame A, will not come in contact with the bottom of the box, so as to become wrinkled or injured. The 35 frame A is provided with the series of hooks D D at the ends, or, instead, if desired, at its sides, and the fringe C is folded back and forth across the frame and placed upon the hooks, as shown. The hooks D D might be secured 40 directly to the frame A; but we prefer to first secure them to the strips E E, of some flexible material—such as leather, strong cloth, or tape—and then secure the strips to the frame by means of small nails or otherwise, so that 45 the hooks may be taken in the hand and more readily passed through the folds of the fringe or other material to be placed in the frame.

F is the back covering of the frame A. This may be of paper, pasteboard, cloth, or 50 other suitable material to fully protect the trimmings held in the frame from dust; and cover F may be made continuous; or, if desired, it may be slotted, as shown at F', so that

the end C' of the goods placed in the frame A may be brought through the slot, as shown, for 55 convenience in exhibiting the goods.

At its ends, or, if desired, at its sides, the frame A is provided with the lifting-rings G G, by which the frame A may be conveniently raised out of and lowered into the box B and 60 otherwise handled.

Constructed in this manner it will be seen that the goods may be easily put in the frame A, and that when in the frame the goods may be 65 very nicely kept in hanging position, so that they will not become crushed in the box and folded down or wrinkled; and, besides, by means of the frame the goods may be very easily handled and advantageously exhibited to customers. 70

Having thus described our invention, we claim as new and desire to secure by Letters Patent—

1. In a show-box for trimmings, the combination, with the frame A, having the series of 75 hooks D D, of the box B, provided with supports b b, for holding the frame above the bottom and within the box, as set forth.

2. The frame A, having hooks D, in combination with the backing F, secured to the 80 frame, and slotted, as shown at F', substantially as and for the purposes set forth.

3. The combination, with box B, provided with posts b b, of the frame A, having holding devices or hooks D, the backing F, slotted at 85 F', and the lifting devices G, substantially as and for the purposes set forth.

4. In a show-box for trimmings, the combination, with the frame A, having the series of hooks D, and the backing F, of the box B, provided with supports b b, for holding the frame above the bottom and within the box, substantially as set forth. 90

5. In a show-box for trimmings, the combination, with the frame A, having the flexible 95 straps E, the series of hooks D, secured to said straps, and the backing F, of the box B, provided with supports b b, for holding the frame above the bottom and within the box, substantially as and for the purpose set forth.

SAM. GUST. BERNSTEIN.
MICHAEL SIMONSON.
